UNITED STATES PATENT OFFICE.

SAMUEL KAHAN, OF NEW YORK, N. Y.

ADJUSTING CLOCKS AND WATCHES TO CHANGES IN TEMPERATURE.

No. 850,887.

Specification of Letters Patent.

Patented April 16, 1907.

Application filed July 31, 1906. Serial No. 328,536.

To all whom it may concern:

Be it known that I, SAMUEL KAHAN, a subject of the King of Great Britain, and a resident of the city of New York, borough of 5 Manhattan, in the county and State of New York, have invented a new and Improved Compensating Device, of which the following is a full, clear, and exact description.

This invention relates to certain improvements in horology, and more particularly to means for compensating for changes in temperature.

The object of the invention is to provide means for varying the length of the suspension-feather of a pendulum, or the hair-spring of a watch, or the oscillating member of any other form of timepiece, so as to offset the variation in length caused by changes in temperature.

My invention is particularly applicable to 20 clocks, and when employed in connection therewith it avoids the necessity for delicately-constructed pendulums and balances composed of various materials.

Reference is to be had to the accompanying drawings, forming a part of this specification, in which similar characters of reference indicate corresponding parts in all the figures, in which—

Figure 1 is a vertical section of one embodiment of my invention, said section being taken on the line 1 1 of Fig. 2. Fig. 2 is a front elevation of the device illustrated in Fig. 1, and Fig. 3 is a transverse section taken on 35 the line 3 3 of Fig. 1.

In the drawings I have illustrated a portion of a clock embodying my invention and comprising any suitable form of support—as, for instance, a frame 5, provided with arms 40 6, extending upwardly therefrom and connected by a cross member 7, from which the pendulum is suspended. As shown, the pendulum comprises a pendulum-bar 8, connected to a feather 9, as is common in clocks of 45 this type. The upper end of the feather is rigidly held within a supporting-block 10, which latter is provided with a short opening 11, serving to support the pendulum. In the rear of the pendulum is supported the 50 pallet-arbor 12, rigidly connected by a bar 13 to the crotch surrounding the pendulum-bar 8. As the pendulum swings from side to side the movement of the crotch oscillates the pallet-arbor and controls the escape- 55 ment in the well-known manner.

The arms 6 are provided with projections

14, extending rearwardly from a point adjacent each side of the pendulum, and at their outer ends they support a bolt 15, directly in the rear of the feather 9. Supported upon 60 this bolt is a thermostatic coil 16, composed of a plurality of layers of different materials—as, for instance, brass and steel—and designed to expand and contract with variations in temperature. The coil 16 is so constructed that it uncoils or expands upon an increase in temperature, and this expansion produces a lateral movement of the free end 17 of the coil equivalent to the variation in the length of the pendulum caused by the 70 same change in temperature. The end 17 of the coil is of a width substantially equal to the distance between the arms 6 6 and lies directly between these arms and in free sliding engagement with both of them. The 75 end intermediate the arms 6 6 is provided with a slot 18 of a width but slightly greater than the thickness of the feather and adapted to normally receive said feather. The end 17 may freely move up and down and 80 prevents any lateral movement of the feather. The weight of the pendulum is supported entirely by the pin 11, and no weight whatever is sustained by the end 17, which latter merely determines the point of 85 oscillation of the pendulum. As the pendulum expands with increases in temperature the coil also expands and the end 17 lowers, so that the working length of the pendulum is identically the same at all 90 times.

The same principle may be applied to watches; but in this case the end 17 of the thermostatic coil would normally inclose the hair-spring adjacent its outer end and the 95 variations in the length of said hair-spring thus readily taken up by varying its effective or working length. In watches the variation in the working length would also compensate for the variation in the operation of 100 the balance-wheel.

Having thus described my invention, I claim as new and desire to secure by Letters Patent—

1. A device of the class described, comprising an oscillating member, means for rigidly supporting one end thereof, a thermostatic coil in engagement with said oscillating member adjacent its point of support and adapted to maintain constant its operating length to compensate for variations in temperature, and means adjacent said coil

for preventing movement thereof other than that caused by changes in temperature.

2. A device of the class described, comprising a pendulum, means for supporting the same, a thermostatic coil having one end thereof rigidly supported and the opposite end thereof in engagement with said pendulum adjacent its point of support and adapted to vary its point of oscillation, and means in engagement with said coil adjacent the last-mentioned end thereof and adapted to prevent movement thereof in the plane of movement of the pendulum.

3. A device of the class described, comprising a pendulum having a supporting-feather, means for rigidly supporting one end of said feather, a thermostatic coil having one end rigidly supported and the opposite free end in engagement with the feather of said pendulum below the point of support, and plates in engagement with the opposite sides of the free end of the coil and adapted to prevent longitudinal movement thereof.

4. A device of the class described, comprising a pendulum having a supporting-feather, means for rigidly supporting one

end of the feather, a thermostatic coil having one end rigidly supported and the other end in engagement with the feather of the pendulum below said point of support and movable in a plane at right angles to the plane of movement of the pendulum, and means for preventing lateral movement of the last-mentioned end of said coil.

5. A device of the class described, comprising a plurality of substantially parallel supporting members, a pendulum having a feather supported adjacent the upper ends of said members and extending therebetween, and a thermostatic coil having one end rigidly supported and the free end of a width substantially equal to the distance between said supporting members and having a slot through which the feather of said pendulum extends, whereby the point of oscillation of the pendulum may be varied to compensate for variations in the length of said pendulum.

SAMUEL KAHAN.
